Primary Examiner — Rosemary K Tarcza*Assistant Examiner* — Christy Nemeth(57) **CLAIM**

The ornamental design for a portable knife rack, as shown and described.

DESCRIPTION

FIG. 1 is a front perspective view of a portable knife rack;
FIG. 2 is a front perspective view thereof;
FIG. 3 is a front elevation view thereof;
FIG. 4 is a rear elevation view thereof;
FIG. 5 is a left side elevation view thereof;
FIG. 6 is a right side view thereof;
FIG. 7 is a top plan view thereof; and,
FIG. 8 is a bottom plan view thereof.

The broken lines shown in the drawings illustrate an environmental knife case that forms no part of the claimed design.
